UNITED STATES PATENT OFFICE.

WILSON C. BERGER, OF CANTON, OHIO.

DESIGN FOR A SIDING-PLATE.

SPECIFICATION forming part of Design No. 21,428, dated March 29, 1892.

Application filed January 29, 1892. Serial No. 419,712. Term of patent 7 years.

To all whom it may concern:

Be it known that I, WILSON C. BERGER, a citizen of the United States, and a resident of Canton, county of Stark, State of Ohio, have 5 invented a new and useful Design for Metallic Siding for Buildings, of which the following is a full, clear, and exact description, reference being had to the accompanying drawings, making part of this specification.

10 My invention relates to a design for a siding-plate for buildings.

In the drawings, Figure 1 is a face view of a portion of the siding-plate, and Fig. 2 is a longitudinal sectional view on line $x-x$ of the 15 preceding figure.

The design consists of a sheet of material having longitudinal grooves a , one above the other, intersected by grooves b at right angles thereto. Each groove has a flat base a' and 20 inclined walls a'' . The sheet is roughened

to present a broken surface of irregular outline in section. The general appearance is that of a series of stone blocks laid one upon the other to break joints.

The leading feature of the design is a sheet 25 of material roughened to present a broken surface of irregular outline in section, and intersecting longitudinal and transverse grooves depressed in the face thereof, each having a flat base and inclined walls. 30

I claim—

The design for a siding-plate, herein shown and described.

In testimony whereof I have hereunto set my hand this 26th day of January, A. D. 1892. 35

WILSON C. BERGER.
